UNITED STATES PATENT OFFICE.

OTTO H. WENDEROTH, OF NEW YORK, N. Y.

GAS-CONTROLLER FOR USE WITH GAS-ENGINES.

1,029,650.

Specification of Letters Patent. Patented June 18, 1912.

Application filed June 3, 1911. Serial No. 631,109.

To all whom it may concern:

Be it known that I, OTTO H. WENDEROTH, a citizen of the United States, and a resident of New York city, in the county of New York and State of New York, have invented certain new and useful Improvements in Gas-Controllers for Use with Gas-Engines, of which the following is a specification.

This invention relates to safety devices for use with gas engines which take their supply of gas from a gas main or house supply.

The object of the invention is to provide a device which will positively prevent the engine from reducing the pressure on the gas main in cases where the engine requires a greater supply of gas at a given pressure than the main may be supplying, in order to prevent robbing the main and lowering the pressure therein, which might cause much trouble to other gas consumers.

A further object is to provide a construction in which the suction of the engine will be prevented from breaking the water seal in case the gas supply on the main is lowered below a predetermined pressure, necessary to properly supply the engine.

Referring to the drawings which form a part of this specification, Figure 1 discloses a vertical sectional view through a machine embodying my invention. Fig. 2 discloses a modified detail of construction.

My construction embodies a very small gasometer of a size depending on the size of the engine employed, and preferably holding just enough gas to properly supply a single charge or two, for each impulse stroke of the engine, and therefore is made of very small capacity compared to other gas holders and may be made at less cost, and to require less space in use.

A, indicates an outer cylindrical shell with a closed bottom A', and B indicates an inner cylindrical shell of sufficiently less diameter to provide an annular chamber C, for holding water D, to form a water seal.

A' indicates a funnel shaped portion of the casing A, provided with a cap A², and serves as a conduit through which the chamber D is supplied with water up to the level of the opening A³ or a short distance above same.

E, indicates a bell of the usual construction employed in gasometers, the depending wall of which rests in the chamber C to form an expansible gas chamber F. The

weight of the bell E and parts carried thereby, is made such as to give the required pressure on the gas to just balance the pressure carried on the main G.

Fastened to the bottom A' of the apparatus is a cylindrical casting H, the lower end of which may be made integral with the flange H', as shown in Fig. 2, or may be provided with a threaded shank portion H² which engages with a thread formed on the inner surface of the flange, and the threaded end of the shank H² projects below the flange and engages with the T I as illustrated. The T I is provided with a threaded nipple I', the top end of which is preferably closed by a plug I², and the lower end by a cap I³.

A jam nut I⁴ is used to hold the nipple in its adjusted position. The nipple is adjusted to serve as a throttle for the gas to prevent a too sudden lowering of the pressure in the main when the engine takes gas from the chamber F, as will be more fully set forth hereinafter.

The top of the casting H is provided with a threaded end H³ on which rests a circular guide J, which is provided with a central guide hole for guiding the lower end of the valve rod K, and which is also provided with passages J'-J' to permit the gas to flow into the chamber L' in the casting L, which casting is threaded at its lower end to engage with the casting H and holds the guide ring J in position as shown. The top of the casting L is provided with a central perforation L² which serves as a guide for the valve rod K, and is also provided with passages L³-L³ to pass the gas into chamber F. A valve-seat L⁴ is formed on the under side of the top of the casting L, and a valve K' is mounted on the rod K and is held against the valve-seat by the spring M, which rests on the ring J and presses the valve against the valve-seat L³ with sufficient force to hold the valve K' to its seat against the weight of the bell E.

The valve rod K extends above the top edge of the shell B, so that the said bell may contact with it to depress it under certain conditions. A casting N, is also connected to the bottom A' and is the same in construction as that of casting H previously described, and is provided with the same character of shank as that indicated by H² and a T outlet similar to T I of the inlet, but the nipple I' is dispensed with and

the lower end of the **T** is closed by a plug **O**. A guide ring **P** of exactly similar construction to that of ring **J**, is located between casting **N**, and casting **Q**, which casting **Q** is the same in construction as casting **L**, except that the valve-seat is located on the outer top side of casting **Q**, and is indicated by **Q'**. A valve rod **R** extends upward to, or nearly to the under side of the bell **E**, and carries a valve **R'** at a predetermined distance above the valve-seat **Q'**.

An abutment ring **R²** is mounted on the rod **R** within the casting **Q** and a spring **R³** is interposed between said abutment ring **15** and ring guide **P** to support the valve **R'** in the normal position shown. The casing **A** is provided with a cover **A⁴** which is secured to the casing by bolts **A⁵**—**A⁵**, and is also provided with a central opening **A⁶**, and a **20** bracket guide **A⁷** which serves to guide the rod **B'** which is mounted on the bell **E** and extends upward through the opening **A⁶** and bracket **A⁷** and carries a ring **S**. A rod **T** is fulcrumed at **T'** and a pull chain **T²** is connected to its opposite end as illustrated. The arrows indicate the inlet and outlet **25** openings for gas.

The operation is as follows: Assuming the gas inlet connected to a gas main supplying gas under the usual pressure, and the outlet connected to a gas engine, and the device filled with air as it would be just after having been erected in condition for use. A by-pass cock on the engine would be **30** opened and the chain **T²** would be pulled down to force the bell **E** to open the valve **K'** against the gas pressure on the main and the spring **M**, thus lowering the valve **R'** toward its valve-seat **Q'**, but not seating said valve. The gas would then flow into and through chamber **F** and from same through the conduit in the castings **G** and **N** and thence to the engine, and when the air had been driven out of the chamber **F** **35** and pipes leading to the engine, and pure gas filled the chamber **F** under the same pressure as that on the gas supply main, the gas pressure should just float the bell **E**, so that normally it would float with the valve **K'** closed and valve **R'** open, substantially as shown in the drawing. When the engine is started the gas is drawn from chamber **F**, thus lowering the pressure therein and causing the atmospheric pressure on the **40** top of bell **E** to force the bell down thus overcoming the pressure of the spring **M**, and admitting gas to chamber **F** and directly through same to the engine so long as the engine is operating on the suction stroke. As soon as the engine ceases to draw **45** gas from the chamber **F**, the gas would continue to flow into said chamber until the bell again floated, thus closing valve **K'**. During the operation of the device as above set forth, the nipple **I'** has been adjusted to

pass just enough gas to supply the engine when operating at its normal rate of speed. Now in case the gas pressure on the main should fall so that the engine could not draw a normal supply, the bell would be drawn **70** down by the suction of the engine to a degree sufficient to seat the valve **R'** on valve-seat **Q'** to close the valve, thereby preventing the water seal in chamber **D** from being broken and also preventing the main gas **75** supply from being dangerously lowered. The nipple valve **I'** also prevents sudden excessive fluctuations of pressure in the gas main which cause flickering of lights supplied from said mains and is used chiefly **80** for this purpose.

Having thus described my invention, I claim as new:

1. A gas controller comprising a casing, valve mechanism for controlling the inflow and outflow of gas from said casing, and means for operating said valve mechanism, so as to stop the inflow of gas into said casing, when the pressure inside the casing rises above the predetermined point, and means for stopping the outflow of gas from said casing, when the pressure inside the **85** casing falls below a predetermined point.

2. A gas controller comprising a casing, valve mechanism for controlling the inflow and outflow of gas from said casing, a floating bell within the casing, said bell being adapted to operate said valve mechanism so as to stop the outflow of gas from said **90** casing when the pressure inside the casing falls below a predetermined point, and means for operating the valve mechanism for stopping the inflow of gas into said casing, when the pressure inside the casing rises above a predetermined point.

3. A gas controller comprising a casing, an inlet for admitting the inflow of gas into said casing, and an outlet for the gas from said casing, a valve located in said inlet and another valve located in said outlet, means for automatically operating the valve controlling the inflow of gas, so as to stop said inflow when the pressure inside the **100** casing rises above a predetermined point, and means for controlling the valve in the outlet for stopping the outflow of gas from said casing when the pressure inside the casing falls below a predetermined point.

4. A gas controller comprising a casing, and a gas inlet and a gas outlet for said casing, a valve located in said inlet and a valve located in said outlet, a floating bell in said casing, said bell being adapted to operate the outlet valve for stopping the outflow from said casing when the pressure in the casing falls below a predetermined point, and means for operating the inlet valve, so as to stop the inflow of gas into **110** said casing when the pressure within the casing rises above a predetermined point.

5. A gas controller comprising a casing, a gas inlet and a gas outlet for said casing, a valve located in said inlet, a spring operating on said valve so as to normally 5 keep it closed, a valve in said outlet and a spring operating on said outlet valve to normally keep it open, a floating bell within the casing, said bell being adapted to open said inlet valve when the pressure 10 within the casing falls below a predetermined point, and to close said outlet valve when the pressure falls below a predetermined point lower than the first mentioned predetermined point.
- 15 6. A gas controller comprising a casing, valve mechanism for controlling the inflow and outflow of gas from said casing, a floating bell within the casing, said bell being adapted to open the gas inflow when the 20 pressure within the casing falls below a predetermined point, and to close the gas outflow when the pressure within the casing falls below another predetermined point.
- 25 7. A gas controller comprising a casing, valve mechanism for controlling the inflow and outflow of gas from said casing, and means for operating said valve mechanism so as to stop the inflow of gas into said casing when the pressure inside the casing rises 30 above the predetermined point, and means for stopping the outflow of gas from said casing when the pressure inside the casing falls below a predetermined point, and an auxiliary device for regulating the inflow of gas.
- 35 8. A gas controller comprising a casing, a gas inlet located in said casing comprising a chamber having a valve-seat, a valve located in said chamber and having an upwardly projecting stem, a spring actuating 40 said valve upwardly against its seat, a gas outlet having a valve-seat, a valve for said outlet having an upwardly projecting stem, a spring operating on said valve, so as to hold it away from its seat, a floating bell 45 within the casing, said bell being adapted to contact with the said valve stems, and serving to open the inlet valve when the pressure within the casing falls below a predetermined point, and to close the outlet valve when the pressure within the casing falls below a lower predetermined point.
- 50 Signed at New York city, in the county of New York and State of New York this 29th day of May A. D. 1911.
